(57) **CLAIM**

The ornamental design for a controller hatch cover, as shown and described.

DESCRIPTION

FIG. 1 is a perspective view of a controller hatch cover and paddles showing the new design;

FIG. 2 is a top plan view, thereof;

FIG. 3 is a front elevational view, thereof;

FIG. 4 is a bottom plan view, thereof;

FIG. 5 is a rear elevational view, thereof;

FIG. 6 is a left side elevational view, thereof;

FIG. 7 is a right side elevational view, thereof;

FIG. 8 is an exploded perspective view, thereof;

FIG. 9 is a top plan view of FIG. 8, the paddles being removed;

FIG. 10 is a front elevational view of FIG. 8, the paddles being removed;

FIG. 11 is a bottom plan view of FIG. 8, the paddles being removed;

FIG. 12 is a rear elevational view of FIG. 8, the paddles being removed;

FIG. 13 is a left side elevational view of FIG. 8, the paddles being removed;

FIG. 14 is a right side elevational view of FIG. 8, the paddles being removed;

FIG. 15 is a perspective view thereof, shown in an environmental use;

FIG. 16 is a top plan view of FIG. 15;

FIG. 17 is a rear elevational view of FIG. 15;

FIG. 18 is a front elevational view of FIG. 15;

FIG. 19 is a perspective view thereof, with paddles removed and shown in an environmental use;

FIG. 20 is a top plan view of FIG. 19;

FIG. 21 is a rear elevational view of FIG. 19; and,

FIG. 22 is a front elevational view of FIG. 19.

The broken lines indicate unclaimed portions and environment and form no part of the claimed design.

1 Claim, 14 Drawing Sheets
